UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR.

1,139,114.

Specification of Letters Patent. Patented May 11, 1915.

Application filed August 4, 1914. Serial No. 854,947.

To all whom it may concern:

Be it known that I, JOHN M. FEDDERS, a citizen of the United States, residing at Buffalo, in the county of Erie and State of New York, have invented new and useful 5 Improvements in Radiators, of which the following is a specification.

This invention has for its object the production of a core for automobile radiators 10 in which a minimum amount of metal is employed to secure a predetermined efficiency and which can be easily constructed and assembled so that the cost of manufacture is reduced to a minimum.

15 In the accompanying drawings: Figure 1 is a fragmentary elevation of a radiator embodying my invention. Fig. 2 is a vertical cross section of the same in line 2—2, Fig. 4. Fig. 3 is a horizontal section in line 3—3, 20 Fig. 2. Figs. 4 and 5 are vertical longitudinal sections in the correspondingly numbered lines in Fig. 2. Figs. 6 and 7 are fragmentary perspective views of two strips of 25 which my improved radiator core is constructed.

Similar characters of reference indicate corresponding parts throughout the several views.

1 represents the upper water inlet header, 30 2 the lower water outlet header, 3 the plurality of upright water passages communicating at their upper and lower ends with the upper and lower headers and 4 a plurality of horizontal air passages arranged 35 between the water passages and extending horizontally fore and aft of the radiator.

The core is built up of a plurality of sheet metal strips each of which is bent to form 40 part of one water passage and part of air passages in one row of the same. For this purpose each strip is bent into zig-zag form so as to produce a succession or series of webs 5 of which adjacent members are arranged at right angles to one another. Each

45 pair of successive webs of one strip form two walls of a square air passage with two adjacent walls of another strip. At opposite longitudinal edges of each strip the same is provided with off-sets 6 which project laterally from the strip in a direction 50 opposite to the side on which the air passages are formed and the off-sets of each strip engage with and are secured to the off-sets of an adjacent strip by solder, or

otherwise, so as to form a tight water passage 55 between adjacent strips. Of the two strips forming a water passage one of them has some of its corners left full, as shown at 7, and others of its corners bent reversely inwardly as shown at 8 so as to form an external concave seat, said full corners and 60 reversely bent corners alternating with each other. In a similar manner the other strip of the two forming a water passage between them has some of its corners left full, as 65 shown at 9 and others of its corners bent reversely outward, as shown at 10. The full corners 7 are inner corners and the full corners 9 are outer corners of a completed 70 water passage. The corresponding full corners of two adjacent strips forming a water passage are adjacent to each other and the corresponding reversely bent corners of the same are also adjacent to each other.

In the assembled condition of the strips 75 the outer full corners 9 of each strip engage with the seats 8 of a strip forming part of an adjacent water passage, thereby interlocking the several strips and holding the same in place relatively to each other during 80 the operation of building the core and soldering its members together.

Owing to the reversely bent corners 10 clearance spaces are formed between the same and the reversely bent corners 8 so as 85 to avoid obstructing the interior of the water tubes and permit a free flow through the same. The strips are connected by solder or otherwise with the upper and lower headers to form a water tight joint with 90 the same, and the upper and lowermost air passages of the several rows are closed against the entrance of water from the header by connecting the upper and lower ends of each pair of strips between which a 95 row of air passages is formed, this connection being preferably effected by seams 11, as shown in Fig. 2.

It is to be noted that in this radiator core the entire inner surface of the water passage 100 is engaged by the water so that the maximum cooling efficiency of the metal is obtained as the air passes through the air passages.

The strips of the radiator can be made 105 quickly and accurately by tools of comparatively simple construction and the assembling of the strips can be effected quickly

without requiring special skill, thereby enabling these cores to be made rapidly and at low cost.

I claim as my invention:

- 5 1. A radiator core having water and air passages arranged at right angles to each other and comprising a plurality of strips each of which is bent to form a plurality of webs which are arranged zig-zag and at 10 right angles relatively to each other, and successive webs forming two walls of a square air passage, some of the corners of the strip being full and others bent reversely into concavo-convex form, said full 15 corners alternating with said reversely bent corners, a plurality of such strips being assembled so that each strip forms a zig-zag water passage with one adjacent strip and a plurality of air passages with another 20 adjacent strip, each air passage being formed by two walls of one strip and two walls of another strip, the two strips forming one water passage having their reversely bent corners adjacent to each other in pairs 25 so that one reversely bent corner projects into the respective water passage and forms a seat therein while the companion reversely bent corner projects outwardly from said water passage and forms a clearance space 30 between the same and the companion inwardly projecting corner, and the full corners of each strip engaging with the seats formed by the inwardly projecting corners of the adjacent strip which together form 35 air passages therebetween.

2. A radiator core having water and air passages arranged at right angles to each other and comprising a plurality of strips

each of which is bent to form a plurality of webs which are arranged zig-zag and at 40 right angles relatively to each other, and successive webs forming two walls of a square air passage, some of the corners of the strip being full and others bent reversely into concavo-convex form, said full corners 45 alternating with said reversely bent corners, a plurality of such strips being assembled so that each strip forms a zig-zag water passage with one adjacent strip and a plurality of air passages with another adjacent 50 strip, each air passage being formed by two walls of one strip and two walls of another strip, the two strips forming one water passage having their reversely bent corners adjacent to each other in pairs so that one reversely bent corner projects into the respective water passage and forms a seat therein while the companion reversely bent corner projects outwardly from said water passage and forms a clearance space between the same 55 and the companion inwardly projecting corner, the full corners of each strip engaging with the seats formed by the inwardly projecting corners of the adjacent strip which together form air passages therebetween, and 60 opposite edges of each strip having off-sets which engage with the corresponding off-sets of the strip with which the same forms a water passage.

Witness my hand this third day of Au- 70
gust, 1914.

JOHN M. FEEDERS.
